WEATHER COVERING MATERIAL

Donald Tulloch, Jr., Holly Oak, Del.

Application March 10, 1943, Serial No. 478,621

6 Claims. (Cl. 108—8)

This invention relates to composition or rigid weather surfacing elements, and more particularly to roofing and siding strips molded from a plastic mass of cement-asbestos or other suitable composition which sets into hardened or indurated character. The strips are provided with transverse or vertical ribs or elevations on the weather exposed surface and so disposed to simulate individual shingles and prevent them from curling.

Generally described, the invention comprises roofing or siding strips which are of substantial lengths provided with transverse or vertical ribs or elevations to reinforce the strips and prevent them from curling, particularly at the weather exposed butt edge, ends and corners. Moreover, the transverse or vertical ribs or elevations can be arranged to give a decorative design, such as being spaced apart to set off the weather exposed surface of the strips in the form of simulated individual shingles or other decorative designs. The ribs or elevations may be of gradually diminishing thickness from the weather exposed butt edges of the strips to the upper or lap marginal edge. They preferably do not extend into the upper or lap marginal edge over which the bottom of a similar strip laps.

In order to further prevent curling at the ends and corners of the shingles, the nailing means, particularly the end nailing means, is either applied in vertical or transverse alignment with the end reinforcements or in an area of the lap edge which is between the end ribs or elevations and the ends of the strips were the ribs or elevations extended.

The opposite ends of the strips or shingles may be rabbeted in order that the strips when laid end to end in courses on the roofing structure will interfit.

For a better understanding of the invention, reference is made to the accompanying drawing, in which:

Fig. 1 is a perspective view of a roof section comprising weather surfacing elements embodying the invention;

Fig. 2 is a partial vertical section on line 2—2 of Fig. 1;

Fig. 3 is a perspective view of one of the weather surfacing elements viewed from the upper edge of the element;

Fig. 4 is a partial section on line 4—4 of Fig. 1; and

Fig. 5 is a perspective view of a weather surfacing element showing a modification of the nailing means.

Referring specifically to the drawing, in which

like numerals are used to designate like parts, numeral 1 shows a surface, such as a sheathing of a wall or roof structure, which is covered with lapped courses 2 of strips 3 laid in end to end relation. The strips may be made of any composition usually employed in making tile or other composition shingles or siding strips. One preferred composition which is especially suitable for the invention is a composition composed of 5 cement and asbestos. The mixed mass is molded by conventional methods in suitable molds, between forming rolls or in hydraulic presses.

The strips are of indefinite length and width, but are advantageously formed in strips equal to 10 about the width of three or four individual shingles. Usually they are about thirty-six inches long.

The strips are provided with ribs or elevations 15 transversely disposed at spaced intervals along 20 the length of the strips. The ribs or elevations may be of any design but are preferably continuous and gradually sloped away at 5 to merge with the body or intermediate portions 6 of the strip between the elevations. The ribs do not 25 extend throughout the width of the strips but only for the width of the portion which is to be exposed to the weather. They are shown in the present embodiment of equal elevation throughout their widths, but they may gradually diminish 30 in thickness from the butt edge 7 to the lap portion 8 on the upper face side of the strip. The lap portion is preferably two or more inches wide.

The marginal elevations or ribs 4a and 4b at 35 the end of the strips are one half as wide as the intervening ribs or elevations 4, and rib 4a is set back from the edge of the strip while rib 4b projects over the opposite edge of the strip equal to the set back distance of rib 4a. Accordingly the 40 ends of the adjacent strips will interfit and form rabbet joints 9 when laid.

Recesses 10 for nails are provided in the upper 45 margins of the strips along the lap which is to be covered by the bottom margins of strips in an overlying course. The recesses for the nails are preferably in medial vertical alignment with the elevations or ribs, particularly the end ribs or between the edges of the strips and the areas in the lap which are in alignment with the ribs or elevations. The nails thus cooperate with the ribs or elevations and in these end areas hold down 50 the ends of the shingles so that they may be prevented from curling by reason of the ribs or elevations.

There is a greater tendency for the shingles to 55 curl at the weather exposed corners, and thus the

elevations and the nailing may be placed there. The ribs or elevations extenuate the thickness of the strips and simulate a more massive appearance.

In Fig. 5 the nailing means are not in medial vertical alignment with the channels or elevated portions or between the edges and the areas of the lap portion which is in alignment, but are closely adjacent thereto in order that the nailing means may be in position to cause the ribs to prevent any curling of the bottom corners of the strips. The outside or extreme end nailing means should be in vertical alignment with the main portion of the ribs or where the ribs merge into the body of the strips.

Having described the invention and certain embodiments to exemplify it, I claim:

1. A rigid weather covering unit composed of indurated hydraulic cement composition material and having the weather exposed surface divided into a plurality of individual shingle simulating areas, an integral vertically disposed portion of greater thickness on each marginal end of the unit to reenforce same and prevent the exposed corners from curling, and nailing portions provided closely adjacent each of the vertical portions of greater thickness to cause the marginal ends of increased thickness to prevent the exposed corners of the unit from curling.

2. A rigid weather covering unit composed of indurated hydraulic cement composition material and having the weather exposed surface divided into a plurality of individual shingle simulating areas, an integral vertically disposed portion of greater thickness on each marginal end and between adjacent individual shingle simulating areas of the unit to reenforce same and prevent the exposed corners from curling, and nailing portions provided closely adjacent each of the vertical portions of greater thickness to cause the marginal ends of increased thickness to prevent the exposed corners of the unit from curling.

3. A rigid weather covering unit composed of indurated hydraulic cement composition material and having the weather exposed surface between integral vertically disposed marginal portions of greater thickness than the portions therebetween to prevent the exposed carriers of the unit from

curling, and a nailing portion provided closely adjacent each of the vertical portions of greater thickness to cause the marginal ends of increased thickness to prevent the exposed corners of the unit from curling.

4. A rigid weather covering unit composed of indurated hydraulic cement composition material and having the weather exposed surface between integral vertically exposed marginal portions of greater thickness than the portions therebetween, the marginal portion of increased thickness being slightly spaced back from one end of the unit and the marginal portion of increased thickness being slightly projected beyond the opposite end and complementary with the opposite end, and a nailing portion provided closely adjacent each of the vertical portions of greater thickness to cause the marginal ends of increased thickness to prevent the exposed corners of the unit from curling.

5. A rigid weather protecting covering comprising lapped courses composed of covering units composed of indurated hydraulic cement composition material and having the weather exposed surface between integral vertically disposed marginal end portions of greater thickness than the portions therebetween to prevent curling of the weather exposed corners of the units, and nailing means provided closely adjacent each of the vertical thickened end portions and covered by the overlying units, the closely adjacent nailing means preventing the exposed corners of the unit from curling.

6. A rigid weather protecting covering comprising lapped courses composed of covering units composed of indurated hydraulic cement composition and having the weather exposed surface between integral vertically disposed marginal end portions of greater thickness than the portions therebetween, said vertically disposed marginal end portions terminating short of the upper edge to provide a lap, and nailing means provided in the lap closely adjacent the ends of the units and covered by overlying units whose butt edges are aligned with the ends of the thickened portions, the closely adjacent nailing means preventing the exposed corners of the unit from curling.
